UNITED STATES PATENT OFFICE.

ALEX MORAR, OF OMAHA, NEBRASKA.

DESIGN FOR A NECKTIE OR SIMILAR ARTICLE.

59,563.

Specification for Design.

Patented Nov. 1, 1921.

Application filed March 31, 1921. Serial No. 457,528. Term of patent 3½ years.

To all whom it may concern:

Be it known that I, ALEX MORAR, a subject of Rumania, residing at Omaha, county of Douglas, and State of Nebraska, have invented a new, original, and ornamental Design for a Necktie or Similar Article, of which the following is a specification, reference being had to the accompanying drawing, forming part thereof.

The figure is a plan view of a necktie, showing the design.

I claim:

The ornamental design for a necktie or similar article, as shown.

ALEX MORAR.
